UNITED STATES PATENT OFFICE

ABRAHAM PERLMAN, OF NEW YORK, N. Y.

DOOR OPERATING AND LOCKING MECHANISM

Application filed April 30, 1930. Serial No. 448,596.

This invention relates to door operating and locking mechanisms and is particularly designed for use in connection with the cell doors of a prison.

The object of the invention is to provide a positive mechanically operated mechanism by means of which each and every door in the system may be locked in either open or closed position and when unlocked 10 may be opened or closed by the positive mechanism operated by the keeper from any distant point, such as outside the corridor from a control box to which he has the key to render the mechanism accessible 15 for operating the doors. The doors may be conveniently arranged and connected in groups and any and all doors of one group, or of all groups, operated from the control box, or any number of selected doors may 20 be operated simultaneously. The doors may be opened and locked in their respective open positions without interfering with the operation of the other doors.

To carry out the above and other objects 25 of the invention, which will appear from the description of the mechanism as shown in connection herewith, positive mechanical devices are employed, which are simple in their construction and not easily tampered 30 with or prevented from performing their required functions and which are easily operated by the person authorized, all of which will appear more fully in connection with the description of the operative embodiment of the invention illustrated in the 35 accompanying drawings, showing the same as designed and applied to a group of sliding doors.

In the drawings, like parts in the several 40 views have been given the same reference numeral.

Fig. 1 is a front elevation, partly in section, of a part of the operating mechanism 45 and one of the doors.

Fig. 2 is an enlarged detail view of one of the individual door locking and releasing devices, being a sectional view on the line 2—2 of Fig. 1.

Fig. 2a is an enlarged detail view, in

front elevation, of some of the parts shown in Figs. 1 and 2.

Fig. 3 is an enlarged detail view, similar to Fig. 2, showing the position of the parts at another point in the operation. 55

Fig. 4 is a front view, partly in section and partly in diagrammatic form, of the operating mechanism in the control box, which is located at the left of Fig. 1.

Fig. 5 is a sectional view taken on the line 5—5 of Fig. 4, being a continuation of the left hand end of Fig. 1.

Fig. 6 is an enlarged sectional view taken on the line 6—6 of Fig. 5.

Fig. 7 is an enlarged sectional plan view, 65 taken on the line 7—7 of Fig. 5.

Fig. 8 is an enlarged detail view, in section, of one of the selective operating elements of Figs. 4, 5 and 6.

The cell doors, one of which is indicated 70 at 1, are hung from T-bars 2, it being understood that for the purpose of illustration only one door is shown and the mechanism is described in connection therewith, the same being duplicated for other doors of 75 the series. A bar 3 is attached to the T-bar 2 and extends on either side of the door structure. This bar 3 carries the rollers 4 which ride upon the track 5 when the door is opened and closed by the actuating mechanism hereinafter described. A housing 6 encloses the mechanism and a guide rail 7 is engaged on its under side by rollers 8 carried by the door structure to hold the door rollers 4 on the track 5. These rollers 80 are preferably flanged to prevent the same from leaving their respective tracks while 85 permitting a free movement of the door.

The actuating mechanism comprises an actuating bar 9 mounted for longitudinal 90 movement (Fig. 1), riding on rolls 10 which roll on the upper face of the rail 7, the movement being restricted by the lugs 11 on the upper face of said rail 7. The bar 9 is also held in position on the rolls 10 by the guide 95 rolls 12 carried by the supports 13 from rail 7.

This actuating bar 9 carries a number of locking pins 14, one for each door, which are mounted for free vertical movement in 100

guides 15 on the actuating bar 9 and are positioned to engage in slots, such as indicated at 16, in the bar 3 of the door structure and when so engaged connect the door with the 5 actuating bar 9 and by means of which the several doors are, selectively, opened and closed by the movement of the bar 9.

The actuation of the operating mechanism will be seen from Figs. 4 and 5. The enclosing casing 64 for the control mechanism is attached to the casing 6, as shown in Fig. 5, and a removable door, 65, is provided with suitable locking means, which prevents access to the control and operating mechanism 10 except when the door 65 is opened by the keeper or other person provided with the key thereto. When the door 65 is opened, the handle 45 is grasped by the operator and pulled downwardly, moving the levers 43 and 44 about their respective pivots, 46 and 46', raising the link 47 connected to the lower end of the lever 43 at 48 and at its upper end 49, to a bell-crank lever 50, which is swung about its pivot 51. The opposite end 20 of the lever 50 is connected at 52 to a link 53 which, in turn, is connected at 54 to the lever 55, which is pivotally mounted at its lower end 56 and connected at its upper 57 to a connecting bar 58. A guide rail 60 is 25 engaged by a guide roll 59 carried by the lever 55, the roll 59 being flanged maintains the several members in position and alignment during their movement, as will be understood.

30 At the inner end of the connecting bar 58 a gear 61 is mounted, which gear rides upon a fixed gear rack 62 and operates a movable gear rack attached to or formed in the end of the actuating bar 9, indicated at 63. The 35 effect of this connection is to impart twice the amount of linear movement to the actuating bar 9 as is imparted to the bar 58 by means of the mechanism just described, as will be seen.

40 A roller 17 is mounted in the lower end of the locking pins 14, permitting the locking pins which are disengaged from the door structure, i. e., in raised position, to ride freely on the rail 3a, mounted on top of the 45 bar 3 attached to the door structure, as the actuating bar 9 carrying these pins 14 is operated for the opening and closing of other doors.

45 A door lock control shaft 18, preferably hollow, is mounted in and extends through the housing 6 (Fig. 1) above all of the cell doors of the cell block. This shaft extends into the operating mechanism housing 64 (Figs. 4-5) and at this end of the shaft 18 a 50 crank 19 is attached, which is connected by a link 20 to a crank 21 on the hand wheel shaft 22, operated by the hand wheel 23. An indicator disk 24 is also carried by this latter shaft 22, the hand wheel 23 and disk 55 24 being positioned on opposite sides of an

inner partition 25 in the housing 64, which partition is provided with a sight opening through which the markings on the disk are visible to determine the position of the mechanism, as shown in Figs. 4 and 5. By 70 means of the hand wheel 23, the disk 24, shaft 22 and crank 21 may be rotated approximately 180 deg. into three positions, indicated on the disk by the notations "Locked," "Center" and "Open all," which 75 are selectively brought into register with the sight opening, rotating the lock control shaft 18 correspondingly, as will be explained hereinafter.

The locking and operating mechanism provided for each door is shown in Figs. 1 to 3 for one door and will be so described but it will be understood that the same applies to any desired number of doors, which may be selectively operated in the 80 same manner. A clutch member 26 is attached to the control shaft 18 and a co-operating clutch member 27 is positioned adjacent thereto on the shaft 18 but is independently rotatable thereon. A lug 28 projects 85 from the face of clutch member 26 and is positioned and arranged to engage a lug 29 projecting from the adjacent face of the clutch member 27 when the clutch member 26, rotated by the shaft 18, is moved 90 to either of its extreme positions, approximately 180 deg. apart. One of these positions is shown in Fig. 3, corresponding to the "locked" position indicated on the disk 24 in Fig. 4. Lugs 30 and 31 project from the periphery of the clutch member 27 and also another lug 32 to which a flexible 95 cable 33 is attached for rotating the clutch member 27, as will be explained hereinafter.

An auxiliary shaft 34 is provided for 100 each door mechanism, mounted in the housing 6, as shown in Fig. 1. On this shaft 34 a locking dog 35 is attached, positioned below and adjacent the clutch members 26 and 27. This locking dog 35 is provided 105 with a projecting ear 36 extending (in one position, Fig. 2) between the lugs 30 and 31 of the clutch member 27. A second ear 37 also projects from the locking dog 35, being spaced from the ear 36 to permit the 110 lug 31 to be moved therebetween, as indicated in the two positions shown in Figs. 2 and 3.

With the parts in the position shown in Fig. 3, the door is locked, either open or closed, the lower end or foot of the locking dog 35 being engaged in the slot 16 of the door structure previously described, the locking dog being held in this position by the ear 36 engaging lug 31 of clutch member 27.

If now the clutch member 27 is rotated, clockwise, either by rotating the shaft 18 by means of the hand wheel 23 (Fig. 4) to the "open all" position, as previously described, 120

causing the lug 28 on clutch member 26 to engage lug 29 on clutch member 27, (unlocking all doors), or by the upward movement of the flexible cable 33 attached to lug 32 of clutch member 27, the lug 31 of clutch member 27 will first engage ear 37 of the locking dog 35 and on further rotation of the clutch member 27 lug 30 engages ear 36, moving the locking dog 35, which also tends to drop by gravity, out of the slot 16 and engagement with the door structure, permitting the locking pin 14 to drop into the slot 16 and thus connect the door (or doors) with the actuating bar 9, as shown in Figs. 1 and 2, (the hand wheel 23 having been returned to the "center" position), permitting the same to be opened or closed by means of the handle 45 and associated mechanism previously described.

The selector mechanism by means of which any one or more doors may be unlocked and operatively connected to the door opening and closing mechanism includes a number of flexible cables, previously mentioned and indicated at 33 in Fig. 2, for operating the clutch members and locking dog for each door. A separate cable is provided for each of said mechanisms and are carried through suitable conduits from the doors to the control housing shown in Figs. 4 and 5.

The inner partition in the housing 64 is extended below the operating hand wheel 23 and is offset in steps, as shown in Figs. 4 and 5, indicated by the numeral 25. The several cables 33 at this end are each connected to a terminal 66, shown in detail in Fig. 8, which terminal is provided with a handle or knob 67 and is mounted for vertical movement in the offset portions of the partition 25. An indicator 68 is snugly and slidably mounted in the terminal 66.

The indicator 68 is provided with a handle or button 69 at its lower end and also with a pin 70 extending through a slot 71 in the side of the terminal 66. A stop pin 72, carried by the partition 25, limits the movement downwardly of the terminal 66 and also controls the movement of the indicator 68 upwardly. A number of indicator control bars, 73, 73a, 73b, 73c, extend transversely of the terminal and indicator and are provided with slots, 74, etc., (Figs. 7 and 8), which permit the pins 70 to pass therethrough when in the position shown in these figures. Cross bars 75, 75a, 75b, 75c, 75d, connect the control bars 73, forming therewith a movable frame which is moved in one direction by the springs 76, 76a, (Fig. 6) and in the opposite direction by a cam arm 77 carried at the end thereof opposite the springs 76, which cam arm is positioned to be engaged by a co-operating cam arm 78 carried by the lever 43 when the same is in

its upper position, shown in Fig. 5. When in this position, the frame is moved into the position shown in Figs. 6, 7 and 8, placing the springs 76 under tension, and when the lever 43 is moved downwardly, to open the doors, this cam arm is disengaged from the cam arm 77 and the springs 76 move the frame to the right, in Fig. 6, and the indicator control bars 73 upwardly in Fig. 7 or to the left in Fig. 8, in which position the pin 70, if the indicator 68 has been moved to its lower position shown in dotted lines in Fig. 8, engages beneath the bar 73 and holds the same in its lower position, in which position the marking "Open" on the same is in sight below the terminal 66. The purpose of this is to indicate that this particular door has been left open.

The operation of this selective mechanism may be briefly explained in connection with one door, it being understood that the same applies to any number of doors or combination of different doors which it is desired to operate.

Assume that door to cell No. 16 is to be opened. The cable terminal 66, together with its indicator 68, is pulled down, (see Fig. 4). This causes the cable 33 connected to the clutch member 27 for that particular door to be moved upwardly at the end attached to said clutch member and moves the clutch mechanism and the locking dog 35 from the position shown in Fig. 3 to that shown in Fig. 2 and unlocking the door while engaging the same with the actuating mechanism, as has been previously described. The swinging of the handle downwardly, operating the actuating bar 9, opens this door and also any other doors similarly connected thereto by the pulling down of the terminal connected to the cable operating the clutch and locking dog for such doors, as will be understood. Moving the handle 45 upwardly closes such doors and the hand wheel 23 is now moved from its "center" position to "locked" position, rotating shaft 18 and clutch member 26 from the position shown in Fig. 2 to that shown in Fig. 3, causing the lug 28 to engage lug 29, rotating clutch member 27 and causing lug 31 to engage ear 36 on the locking dog 35, moving the same into engagement with the slot 16 of the door structure and raising the locking pin 14 out of engagement therewith. This operation also pulls the cable 33 and moves the terminal, together with its indicator, 66-68, back to its upper position, the pin 70 passing through the slot 74 in the control bar 73, which has been moved by the engagement of the cam members 77-78, previously described.

Should it be desired to lock the door in its open position, the hand wheel 23 and associated parts are operated as described for locking in the closed position, but as the

lever 43 is then in its lower position the cam members 77-78 are not engaged and the springs 76 have moved the control bar 73 so that the pin 70 on the indicator 68 is engaged beneath the same and the indicator 5 is held in its lower position, indicating that this door is open.

To unlock the door previously locked in its open position just described, the hand wheel and associated mechanism is moved to 10 the "open all" position, operating the clutch members in the manner previously described. In this case, the locking dog indicated at 35' mounted on the same auxiliary shaft 34 (Fig. 1) is operated as described to lock and unlock the door in this 15 position. That is, the door structure has been moved to the right, bringing the slot 16 opposite the locking dog 35' instead of 35, the operation of both of these is the 20 same, as both are mounted on the same shaft.

The rail 3a (Fig. 1) attached to the upper side of the bar 3 of the door structure extends beyond the ends of this bar so that 25 as the door is open or closed and the actuating bar 9 moved to operate some other door the locking pin 14 will not drop and engage the end of the bar 3. This also permits the door—or any or all doors—to be 30 unlocked in their open position, as when the prisoners are out for meals, etc., and upon returning can close their particular door without requiring the keeper to operate the mechanism separately as each one returns. 35 Upon closing his door, the locking pin falls into the slot, if the actuating bar has been set in the closed position, and the door prevented from being opened, or if the actuating bar is set in the open position any 40 and all doors may be either opened or closed independently of the locking mechanism or operating mechanism. This is sometimes desirable, as when the cells are being cleaned or inspected, etc., and provides a mechanism 45 which is adapted to all conditions and requirements.

What I claim as new and desire to secure by Letters Patent is:—

50 1. Door operating and locking mechanism of the class described comprising the combination with a number of cell doors each independently mounted and adapted to be moved into open or closed position, of an actuating member extending adjacent and adapted to be operatively connected to a predetermined number of said doors, a separate locking pin for each of said doors adapted to operatively connect said actuating member with said doors, a separate locking dog for each of said doors pivotally mounted and adapted to be swung into position to selectively disengage said locking pin therefrom and to lock said door against movement, a control shaft extending adja-

cent all of said locking doors, a pair of co-operating clutch members for each door one clutch member of each pair being attached to said control shaft and the other being pivotally mounted thereon and positioned and adapted to operate one of said locking dogs, means for rotating said control shaft and clutch members to operate said locking dogs, and means for operating said actuating member to open and close said doors. 70

2. Door operating and locking mechanism of the class described comprising the combination with a number of cell doors each independently mounted and adapted to be moved into open or closed position, of an actuating member extending adjacent and adapted to be operatively connected to a predetermined number of said doors, a separate locking pin for each of said doors adapted to operatively connect said actuating member with said doors, a separate locking dog for each of said doors pivotally mounted and adapted to be swung into position to selectively disengage said locking pin therefrom and to lock said door against movement, a control shaft extending adjacent all of said locking dogs, a pair of co-operating clutch members for each door one clutch member of each pair being attached to said control shaft and the other being pivotally mounted thereon and positioned and adapted to operate one of said locking dogs, means for rotating said control shaft and clutch members to operate all of said locking dogs simultaneously, means for selectively operating any one or more of said locking dogs, and means for operating said actuating member to open and close said doors. 90

3. In a door operating and locking mechanism, the combination with mechanism for opening and closing the doors connected thereto, of individual locking means for each door and each comprising a locking dog arranged to be engaged with said door to lock the same or to be disengaged therefrom and simultaneously cause the door to be connected with said opening and closing mechanism, said locking means including a clutch operable either from a common operating means or selectively operated to unlock and connect said door with said opening and closing mechanism. 105

4. In a door operating and locking mechanism, the combination with mechanism for opening and closing the doors connected thereto, of individual locking means for each door each comprising a locking dog and a clutch member, said locking dog being adapted to be engaged or disengaged with the door by said clutch member, said clutch member being operable either by a common operating means or selectively operated for one or more of the doors, and a locking pin adapted to connect a door with 110

the opening and closing mechanism of the doors, the operation of said pin being controlled by the operation of said locking dog.

5. In a door operating and locking mechanism, the combination with mechanism for opening and closing the doors connected thereto, of a clutch device for each door comprising co-operating clutch members one of which is connected to and operated by a common operating shaft and the other of which is adapted to be engaged and operated by the first member in its extreme positions and also being provided with portions positioned and adapted to engage and operate a locking member, a locking member for each door positioned and adapted to be operated by said last named clutch member, means for rotating said common operating shaft to simultaneously operate all of said clutch devices, an independent operating means comprising separate connecting means for said last named clutch members of each of said clutch devices for selectively and independently rotating said clutch members, individual clutch devices and locking members being provided for each door adapted to be simultaneously operated or to be selectively operated by said independent operating means.

30 6. In a door operating and locking mechanism, the combination with mechanism for opening and closing the doors connected thereto, of a clutch device for each door comprising co-operating clutch members one of which is connected to and operated by a common operating shaft and the other of which is adapted to be engaged and operated by the first named member in its extreme positions and also being provided with portions positioned and adapted to engage and operate a locking member, a locking member for each door positioned and adapted to be operated by said last named clutch member, means for rotating said common operating shaft to simultaneously operate all of said clutch devices, an independent operating means, said independent operating means comprising a number of flexible cables each connected to one of said last named clutch members, said cables being arranged and adapted to selectively and independently rotate said clutch members, individual clutch devices and locking members being provided for each door and adapted to be simultaneously operated or to be selectively operated by said operating means.

60 7. In a door operating and locking mechanism, the combination with mechanism for opening and closing the doors connected thereto, of individual locking means for each door and operating means operatively associated therewith, means comprising individual flexible cables each connected to one of said operating means, individual handles

connected to said cables, individual indicators carried by said handles, and means operated by said opening and closing mechanism for controlling said indicators.

70 8. In a door operating and locking mechanism, the combination with mechanism for opening and closing the doors connected thereto, of individual locking and operating means for each door, means comprising flexible cables each connected to one of said operating means, individual handles connected to each of said cables, a slideable indicator carried by each of said handles, said indicators each comprising a rod carried within and movable with one of said cable handles and having a portion positioned to be engaged by a mechanism operated by said opening and closing mechanism adapted to engage said indicators which have been operated and the door associated therewith open and hold the indicator in its open position to indicate the corresponding position of the door.

75 9. In a door operating and locking mechanism, the combination with mechanism for opening and closing the doors connected thereto, of individual locking and operating means for each door, individual locking pins for each door each controlled by the operation of said locking means and adapted to be moved thereby into and out of engagement with said doors and connect and disconnect the same from said opening and closing mechanism, a member carried by each door structure upon which said locking pin rides when disengaged, said member extending on either side of the door structure to hold said pin disengaged therefrom when the locking means is operated with the door open, permitting the door to be moved independently thereof.

Signed at New York city, in the county of New York and State of New York, this 28th day of April, A. D. 1930.

ABRAHAM PERLMAN.
